US00D441450S

(12) **United States Design Patent** (10) Patent No.: **US D441,450 S**
Salvatori et al. (45) Date of Patent: ** May 1, 2001

(54) **DEFIBRILLATOR**

(75) Inventors: **Phillip H. Salvatori**, NW Salem, OR (US); **Kurt Frederick Olsen**, Vancouver, WA (US); **Martin G. Rockwell**, Sherwood, OR (US); **Jonathan Neal Andrews**, McMinnville, OR (US); **Stephen Vance Cooper**, Amity, OR (US)

(73) Assignee: **Agilent Technologies, Inc.**, Santa Clara, CA (US)

(**) Term: **14 Years**

(21) Appl. No.: **29/102,771**

(22) Filed: **Mar. 31, 1999**

(51) LOC (7) Cl. **24-01**

(52) U.S. Cl. **D24/167**

(58) Field of Search D24/167, 169, D24/165; 607/5, 6, 522, 523
